UNITED STATES PATENT OFFICE.

AARON COLEMAN, OF NEW YORK, N. Y.

DESIGN FOR A SUSPENDER-BUCKLE.

SPECIFICATION forming part of **Design No. 28,560, dated May 10, 1898.**

Application filed March 19, 1898. Serial No. 674,530. Term of patent 7 years.

To all whom it may concern:

Be it known that I, AARON COLEMAN, of the city of New York, (borough of Manhattan,) in the county and State of New York, have 5 invented and produced a new and original Design for a Suspender-Buckle, of which the following is a full, clear, and exact description.

Reference is to be had to the accompanying drawing, forming a part of this specification, 10 in which the figure is a perspective view of a suspender-buckle showing my design.

The design consists of a front plate A, having the configuration of a miniature horseshoe, with a conventionalized frog B extend-

ing from the toe to the heels, the loop-plate C 15 appearing at the rear of the horseshoe, with a serrated upper edge D.

The leading feature of my design consists of the horseshoe-shaped front plate of the buckle. 20

I claim—

A design for a suspender-buckle, as herein shown and described.

AARON COLEMAN.
